D. E. ROSS.
STEERING GEAR.
APPLICATION FILED MAR. 7, 1921.

1,393,973.

Patented Oct. 18, 1921.

Fig. 1.

UNITED STATES PATENT OFFICE.

DAVID E. ROSS, OF LA FAYETTE, INDIANA, ASSIGNOR TO ROSS GEAR & TOOL COMPANY, OF LA FAYETTE, INDIANA, A CORPORATION OF INDIANA.

STEERING-GEAR.

1,393,973.

Specification of Letters Patent. Patented Oct. 18, 1921.

Application filed March 7, 1921. Serial No. 450,482.

To all whom it may concern:

Be it known that I, DAVID E. Ross, a citizen of the United States, residing at La Fayette, in the county of Tippecanoe and State 5 of Indiana, have invented certain new and useful Improvements in Steering-Gears; and I hereby declare that the following is a full, clear, and exact description thereof, reference being had to the accompanying drawings, which form part of this specification.

This invention is an improvement in steering gears, particularly adapted for automobiles, boats, etc. Its object is to provide a steering gear in which motion is transmitted 15 direct from the steering shaft to the rocker shaft in a powerful and efficient manner; and can be readily adjusted as desired in steering the machine; and will hold the rocker shaft securely in any desired adjusted 20 position. A further object is to so construct the gear that the stresses on the rocker shaft due to the transmission will be absorbed or practically counteracted in the rocker shaft itself; thus preventing undue strain on the 25 bearings of the rocker shaft, and the lateral thrust of the actuating member on the steering shaft will be at least in part counterbalanced or counteracted by the rocker shaft construction. The invention provides a very 30 simple, compact, strain absorbing or counter-acting steering gear free from reversibility.

The accompanying drawings illustrate one practical embodiment of the invention, and I will explain the invention with reference 35 to said drawings and set forth in the claims the essentials of the invention and the novel features of construction and novel combination of parts for which protection is desired.

In said drawings:

40 Figure 1 is a view of the steering gear with part of the casing removed, and partly in section, on the line 1—1 Fig. 2.

Fig. 2 is a transverse section, partly in elevation, on the line 2—2 Fig. 1.

45 Fig. 3 is a side elevation of the rocker shaft member and indicating in dotted lines the mode of introducing the threaded ball thereto.

As shown the rocker shaft 1 is mounted 50 in a bearing 2 forming part of a casing, which may be of any suitable construction, and fastened to the chassis or machine

whereon the gear is to be used, by any suitable means. As shown it is secured by a bracket 2^d attached to a beam 2^c of the chassis. 55

The steering arm 1^a may be of any desired construction, and connected in any suitable manner to the outer end of this rocker shaft. Preferably the steering arm 1^a is connected to the rocker shaft 1 by devices as shown in 60 my Patent No. 1,356,579, April 20, 1915.

On the inner end of the rocker shaft is a partispherical head 1^b which, viewed from the side, (see Fig. 3), has an approximately hemispherical lower portion 1^b and an upper 65 quadrant portion 1^c. This partispherical head is adapted to receive a ball 3 which will fit closely and neatly within the interior of this head. The parts 1^b and 1^c extend approximately 270° from end to end around 70 the ball, (see Figs. 2 and 3). To permit this ball to be introduced into the partispherical head of the rocker shaft an arc shaped recess 1^d is made in the front of the part 1^b directly opposite or in line with the 75 rocker shaft. This enables the ball 3 to be inserted into or removed from the head as indicated by dotted lines in Fig. 3, and when so inserted the ball can not be removed from the head either by movement at right angles 80 to the axis of the rocker shaft, or by movement radially thereof.

This ball 3 is keyed or otherwise rigidly fastened to the steering shaft 4 as indicated; said shaft 4 extends at right angles to the 85 rocker shaft 1 as shown, but may be set at any desired inclination to the vertical when the rocker shaft 1 is horizontal.

This ball 3 is provided with a spiral tooth or teeth as indicated at 3^a, which may be of 90 any desired pitch and mesh with an oppositely spirally toothed or ground segment 5, see Figs. 1 and 2, which is preferably set within a shoulder 1^e on the part 1^c of the rocker shaft head and is rigidly fastened 95 thereto in any suitable manner, being shown as secured to part 1^c by rivets 5^b, so that this segment is in effect an integral part of the partispherical head of the rocker shaft.

The segment 5 is diametrically opposed to 100 the central portion of part 1^b of the rocker shaft head, and its threads correspond to and closely engage the teeth 3^a on the exterior of the ball, and the peripheries of the

teeth 3^a have a close peripheral fit against the inner side of the partispherical head of the rocker shaft.

- To permit the segment 5 to swing around the ball and rock the shaft 1, the part 1^b of the rocker shaft head may be provided with diametrically opposite slots in its sides as indicated at 1^f Figs. 2 and 3, so that the shaft 1 and partispherical head can be turned or rocked relatively to the shaft 4 without binding. Referring to Fig. 1, the nut 5 can have a movement of approximately 80° in the casing 2 and the rocker shaft has a corresponding extent of movement.
- 15 The steering shaft 4 may be journaled in suitable bearings in the casing. As shown, this casing comprises a semispherical portion 2^a on the inner end of the bearing 2, and an opposed semispherical portion 2^b, 20 these portions 2^a and 2^b may be provided with peripheral meeting flanges 2^c bolted together as indicated at 2^e in Figs. 1 and 2 of the drawings. The portions 2^a—2^b may be provided with bearings of any suitable 25 kind for the shaft 4^a, as indicated at 6 and 6^a in Fig. 1, such bearings being only conventionally shown.

The steering shaft 4 may be tubular and when applied to an automobile the control 30 rods (not shown) can pass through this shaft 4 and be connected to the usual operating devices on the steering wheel on the upper end of the shaft, and by the usual connections to the devices to be operated 35 below the casing.

Referring to Fig. 1, it will be seen that when the steering shaft 4 is turned the ball 3 will be turned therewith and according to direction of rotation of the steering shaft 4 40 the threads on ball 3^a engaging the segment 5 will cause the latter and the rocker shaft to move right or left with greater or less speed according to the pitch of the teeth 3^a on the ball 3. Any rotation of the shaft 4 45 will cause a rotative movement of the rocker shaft 1, the change of motion being affected immediately and directly by the engagement of the teeth 3^a of the ball with the teeth of segment 5 in the partispherical 50 head of the rocker shaft.

The tendency of the threaded engagement between the parts 3 and 5 to force the segment 5 radially away from the shaft 4 is counteracted and compensated for within 55 the head by the fact that the peripheries of the spiral teeth on the ball engage the inner periphery of the head 1^b at a point diametrically opposite to the segment 5 (see Fig. 2) so that there can be no cramping or 60 distortion of the rocker shaft 1 in its bearing in the casing 2.

I claim:

1. In a steering gear, a rocker shaft having a parti-spherical head on its inner end 65 adapted to receive a ball, and a toothed seg-

ment on said head opposite a diametrically opposed part of said head; with a spirally toothed ball rotatably fitted in said head and engaging said segment and bearing against the inside of the head opposite said segment; and a steering shaft connected to said ball, substantially as described.

2. In a steering gear as set forth in claim 1, the head having diametrically opposite slots in line with the steering shaft to permit oscillatory movement of the segment and rocker shaft relative to the steering shaft when the steering shaft is turned, substantially as described.

3. In a steering gear as set forth in claim 1, a casing inclosing the parti-spherical head, the said casing having bearings for the steering shaft and rocker shaft, substantially as described.

4. In a steering gear, a rocker shaft having a parti-spherical head on its inner end adapted to receive a ball; said head having an opening for the entry of the ball at an angle to the axis of the rocker shaft; and a toothed segment on said head opposite a diametrically opposed part of said head; with a spirally toothed ball rotatably fitted in said head and engaging said segment and bearing against the inside of the head opposite said segment; and a steering shaft extending into said head and connected to said ball, substantially as described.

5. In a steering gear as set forth in claim 3, the head having diametrically opposite slots in line with the steering shaft to permit oscillatory movement of the nut segment and rocker shaft relative to the steering shaft when the steering shaft is turned, substantially as described.

6. In a steering gear as set forth in claim 4, a casing inclosing the parti-spherical head, said casing having bearings for the steering shaft and rocker shaft, substantially as described.

7. In a steering gear; a rocker shaft having a parti-spherical head on its inner end adapted to receive a ball; and a segmental spirally toothed nut attached to said parti-spherical head and lying diametrically opposite part of said head; a spirally toothed ball rotatably fitted in said head and engaging said nut; and a steering shaft extending into and through said parti-spherical head and through said ball, said ball being rigidly attached to the said steering shaft; said head having diametrically opposite slots in line with the steering shaft to permit oscillatory movement of the segment and rocker shaft relative to the steering shaft and ball when the steering shaft is turned.

8. In a steering gear as set forth in claim 7, a casing inclosing the parti-spherical head, said casing having bearings for the steering shaft and rocker shaft, substantially as described.

9. In a steering gear; a rocker shaft having a parti-spherical head on its inner end adapted to receive a threaded ball; said head having an opening for the admission of the ball at an angle to the axis of the rocker shaft, and a segment attached to said head and projecting therein opposite a diametrically opposed part of the head; with a spirally toothed ball rotatably fitted in said head and engaging said nut; and a steering shaft extending through said head and through said ball, the steering shaft being perpendicular to the rocker shaft, and said ball being rigidly attached to the said steering shaft; the said head having diametrically opposite slots in line with the steering shaft to permit oscillatory movement of the nut and rocker shaft relative to the steering shaft and ball when the steering shaft is turned. 15
10. In a steering gear as set forth in claim 9, a casing inclosing the parti-spherical head and having bearings for the steering shaft and rocker shaft, substantially as described. 20

In testimony that I claim the foregoing as 25 my own, I affix my signature.

DAVID E. ROSS.
